UNITED STATES PATENT OFFICE.

MEYER VLAS, OF PATERSON, NEW JERSEY.

CARPENTER'S IMPLEMENT.

Application filed December 27, 1921. Serial No. 525,145.

To all whom it may concern:

Be it known that I, MEYER VLAS, a subject of the Queen of Holland, residing at Paterson, in the county of Passaic and State 5 of New Jersey, have invented certain new and useful Improvements in Carpenters' Implements, of which the following is a specification.

This invention relates to the art of indicating the plane of cutting a rafter or the like so that the face left by the cutting will abut flat against another rafter or the like to which the first rafter is to be joined, and it has reference particularly to that branch 15 of this art which is concerned with indicating the plane of cutting where such plane is perpendicular to no side of the rafter, as in the case of the hip, valley, jack and cripple rafters of a roof. The carpenter, knowing the run and rise of a roof, can by means 20 of the scale provided on certain carpenter's squares determine the angle of cut for an inclined rafter whose end is to abut another rafter face to face and which stands in the 25 plan at right angles thereto; but when the thus inclined rafter stands in the plan oblique to the other rafter he has to depend on certain calculations which ordinary carpenters are unable and which in any event 30 are more or less tedious to perform. The object of this invention, therefore, is to provide an implement whereby a line such as the "plumb-cut" being found, the line complementary thereto to represent the plane 35 of cut may be easily determined.

The invention broadly consists in a pair of rules pivoted together so that each is confined to move in a definite plane and gaging means on one member adjustable 40 toward and from the plane of movement of the latter. For facility of description I have designated the member having the gaging means as the "body member" and the other as the "auxiliary member."

45 In the drawings,

Figure 1 is a perspective view of the implement;

Figure 2 is a side elevation thereof;

50 Figure 3 is a sectional view on line 3—3 Figure 2;

Figure 4 shows an architect's or builder's plan of the valley portion of a roof frame; and

55 Figure 5 shows a rafter and the "plumb-cut" thereon and, in dotted outline, my im-

plement in position for indicating the line complementary to the "plumb-cut."

The body member is shown as a rule *a* having an edge beveled off at the back, as at *b*. At one end of this member is a screw bolt 60 *c* arranged in a plane perpendicular thereto and forming a pivot, and on this pivot is confined to move in a plane parallel to the member *a* the auxiliary member *d*. The member *d* may be secured in any angular 65 relation to the member *a* by tightening the screw bolt; the member *d* may have a longitudinal slot *d'* to receive the screw bolt, whereby member *d* may also be adjusted longitudinally, as in certain cases will be 70 found convenient.

The member *a* has a pair of transverse triangular guides *e* projecting from its front face, perpendicular thereto; grooves *e'* in the adjoining faces of these guides and a 75 longitudinal slot *f* in the member *a* receive a tongue *g* which forms the aforesaid gaging means. This tongue is a flat plate, and since the ways *e'* are perpendicular to the member *a* said tongue stands in a plane perpendicular to and extending longitudinally 80 of said member and is shiftable in said plane so that its working edge *g'* may assume different distances from the back of member *a*.

The lower end of the member *a* as shown 85 in Figs. 1 and 2 I designate its basal end; in the present case it is formed by the outer or lower face of the lower guide *e*, which is perpendicular to the plane of member *a*. At the rear end of the tongue its lower edge 90 has a lug *g''* which projects into coincidence with the plane of said face of the lower guide *e* (see Fig. 2).

The tongue or gage *g* may be held where 95 adjusted by the set-screw *h*.

The implement is used thus: Let *x* represent the already-ascertained "plumb-cut" line found on a timber *A*, Fig. 5, which is to form the rafter *A* (shown also by the builder's drawing represented in Fig. 4) 100 that is to be joined to the valley rafter *B*. The gage or tongue *g* is set in member *a* so that the plane in which its rear edge and the edge *b* of member *a* lie forms a predetermined angle (see Fig. 3) with the plane 105 of member *a* (or, which is the same thing, with the plane of movement of member *d* relatively to *a*). This angle is determined from the builder's drawing (Fig. 4) by setting the implement basal end down on the 110

drawing in the angle between the two rafters A and B and so that, the edge *b* of member *a* being coincident with the apex of the angle, the rear face of said member 5 and the rear end of gage *g* coincide with the lines representing adjoining faces of the two rafters; the lug "g" assists in truing the implement at this time to a perpendicular relation to the drawing. The implement 10 is then transferred to the actual timber (Fig. 5) and placed with the edge *b* of member *a* true to the "plumb-cut" *x* and the corresponding edge of member *d* extending across an adjoining face of the timber, and a line is marked, as at *y*, on the latter face along the edge of member *d*. The lines *x* and *y* will represent a plane, and whatever the angularity of the "plumb-cut" line relatively to the timber this plane 15 will be perfectly vertical or plumb when the rafter A is in place; that is, the end formed on said rafter in said plane will squarely abut the side of the valley rafter B. It will be seen that when the angle is 20 determined as in Fig. 4, it fixes the angular position which member *a* will occupy when placed against the actual timber, and that in turn fixes the plane in which the member *d* moves—in short, the plane of the 25 cut. The carpenter may apply the implement to the same side of the actual timber as it is shown as occupying in connection with the illustration of said timber afforded by Fig. 4, that is, the inner side; but as 30 a timber is usually sawed from near the end inward Fig. 5 shows the implement adapted to the outer side, the plane of the cut not being altered because it will be apparent that the implement is in Fig. 5 re- 35 versed relatively to its position in Fig. 4 and abuts the opposite side of the timber.

To simplify the explanation I have hereinbefore referred to but one edge *b*. Both edges, *b'* as well as *b*, of member *a* will 40 usually be beveled and be working edges, and correspondingly both of the edges of

member *d* will be working edges, and both may also be beveled. Thus the implement can be used interchangeably for indicating planes for cuts whose apices are at either 50 the right or left sides of timbers. Fig. 4 shows the implement on the builder's drawing at points where several different kinds of joints appear.

The bottom surfaces of the lower guide *e* 55 and the lug *g'*, being in a plane perpendicular to the member *a*, afford rests for the implement when placed on the drawing (Fig. 4) and thus insure accuracy in determining the adjustment of the gage *g*. 60

Having thus fully described my invention, what I claim as new and desire to secure by Letters Patent is:—

1. In an implement for use in indicating the plane of cutting a timber crosswise, the combination of a pair of rules pivoted together so that each is confined to move in a definite plane, and a gaging device connected with one rule to move rectilinearly toward and from the plane of movement 70 thereof.

2. In an implement for use in indicating the plane of cutting a timber crosswise, the combination of a pair of rules pivoted together so that each is confined to move in 75 a definite plane, and a gaging tongue penetrating one rule and slidable therein rectilinearly toward and from the plane of movement thereof.

3. In an implement for use in indicating 80 the plane of cutting a timber crosswise, the combination of a pair of rules pivoted together so that each is confined to move in a definite plane, and gaging means on one rule adjustable toward and from the plane 85 of movement of said rule, said rule and the gaging means having rests facing away from the pivot between the rules and lying in a plane substantially perpendicular to 90 said rule.

In testimony whereof I affix my signature.

MEYER VLAS.
